UNITED STATES PATENT OFFICE.

JOHN B. MARTENS, OF CLEVELAND, OHIO, ASSIGNOR TO ALBERT H. BATES, OF CLEVE-
LAND HEIGHTS, OHIO.

DIE-STOCK.

1,289,506.

Specification of Letters Patent. Patented Dec. 31, 1918.

Application filed February 11, 1918. Serial No. 216,577.

To all whom it may concern:

Be it known that I, JOHN B. MARTENS, a citizen of the United States, residing at Cleveland, in the county of Cuyahoga and State of Ohio, have invented a certain new and useful Improvement in Die-Stocks, of which the following is a full, clear, and exact description, reference being had to the accompanying drawings.

10 The object of this invention is to provide a die stock which shall carry thereon a plurality of standard thread dies midway between the handles of the stock, and, to arrange on the stock an adjustable pipe guide, 15 shiftable to operative positions opposite either of the dies and adapted to closely embrace the exterior of pipes of various diameters, on which the dies operate.

Another object is to render the device 20 simple, durable, efficient and easy to operate. This invention is hereinafter more fully described in connection with the accompanying drawings and the essential characteristics are in the summarized claims.

25 In the drawings, Figure 1 is an end elevation of my die stock; Fig. 2 is a central transverse section through the same; Fig. 3 is a plan of my die stock showing a pipe in position to be threaded; Fig. 4 is an irregular sectional detail showing the arrangement of the slide for the pipe guide; Fig. 5 is a central longitudinal section through the die stock and Fig. 6 is a plan view of the guide bushing, a portion being broken away 35 for clearness; Figs. 5 and 6 are on a scale larger than that of the other figures.

Designating the parts by the use of reference characters, 1 indicates a hollow frame contracted at the ends and integral with inwardly turned bosses 3, in axial alignment 40 and threaded to receive the usual tubular handles indicated at 4.

Substantially half of the perimeter of the frame 1 is occupied by standard pipe thread dies 5, and the guides therefor. The guides 45 comprise outwardly extending ribs 6, cut away as shown to engage the outer edges only of the die members, and forming the sides of troughs, the bottoms of which are 50 formed by integral portions 7, of the frame 1. The dies 5, comprise rectangular blocks closely fitting between the ribs 6 and seating on the members 7 and secured thereto by the usual screws 8, while screws 9 extending 55 through bosses 10 provide a slight longi-

tudinal adjustment and hold the dies from receding when in use. The ribs 6 and members 7 comprising the guide ways for the dies are preferably arranged substantially 60 degrees apart, that is, the axes of the dies 60 extend through the axis of the handles and the angle between the axes of the dies is 60 degrees whereby the three sets shown occupy substantially half of the perimeter of the stock frame.

65 Instead of providing the usual collars for guiding the pipes which in this case would require three collars to be set side by side and diametrically opposite their respective dies, I prefer to provide an adjustable bushing adapted to act as a guide for the different sizes of the pipes which the dies in the frame are designed to act upon. I arrange this bushing so that it is carried by the frame and movable around, substantially 70 half of the perimeter of the frame in the zone of the dies and I provide means for holding the bushing diametrically opposite any one of the sets of dies.

75 A brief description of the bushing and 80 its mounting is as follows: Semi-circular shoulders 12, face inwardly from opposite sides of a rectangular opening 14, through which a pipe may extend to any of the dies. Arcuate ribs 15, on the bushing sleeve 16, 85 slidably fit the shoulders 12 and are retained by arcuate strips 17, secured to a shoulder 13, by screws 19. The bushing 16, has an enlarged disk-like head portion 20, on which are pivoted a series of triangular jaws 18, 90 equally spaced apart and each adapted to slidably engage the exterior of a pipe, and, to be brought into engagement therewith, by rotating a cover head 22, having an inwardly turned flange 23 positioned by a 95 flange 24, on the head 20. The arrangement and operation of this adjustable bushing is substantially the same as that shown in the patent of G. P. Bard No. 606,774, granted July 5, 1898.

100 Projections 25, extend outwardly from the jaws into curved slots 26 in the cover 22, while the pivots 27 extend inwardly from the jaws 18, and closely engage recesses in the head 20. It will be seen that a relative 105 rotation of the cover 22 and head 20 will result in swinging the pivots 25 inwardly or outwardly, moving the jaws from the position shown in solid lines in Fig. 6, inwardly to engage the pipe indicated at P. 110

A further movement would bring the jaws into an engagement with the smaller pipe. To clamp the cover plate in any position and thus hold the jaws set to act on a given size of pipe, it is only necessary to provide a screw such as shown at 28 extending through a slot 29 in the head 20 and into the flange 23. This slot is long enough to permit the desired movement while the tightening of the screw holds the cover and jaws 18 in any position. A screw indicated at 30 may extend through a similar slot in the flange 23 opposite the screw 28 or a plurality of screws 30 may be positioned as desired and permanently set to permit a sliding movement, one screw preferably the screw 28 being utilized to tighten the cover to the head.

As a means for clamping the adjustable head in any position in its guide opposite any of the dies, I prefer to provide notches 32 in the inner edges of the strips 17 which notches may receive tongues 33 on the sliding blocks 34 fitted in recesses in the bushing 16 and adapted to be moved inwardly to disengage the tongues from the notches 32 by plungers 35. These plungers have threaded extensions 36 engaging the blocks 34 and are slideable in bosses 38. Springs 39 normally urge the plungers outwardly. The plungers extend but a short distance beyond the periphery of the head 20 and may be depressed by the thumb and finger, to disengage the tongues from the notches 32, thus permitting the entire bushing to swing from one position to another.

From the foregoing description it will be seen, that I have provided a die stock carrying a plurality of standard adjustable pipe dies adapted to act on various sizes of pipe, and which has a guide bushing quickly adjustable to the three sizes of the pipes on which the dies, carried by the stock may act, and also adjustable to larger or smaller sizes of pipe for dies which may be substituted for the usual dies. The device is simple, efficient and has no parts liable to be broken by dropping of the die stock as all the projecting parts are protected by integral or rigid portions of the frame. The dies and bushing are so positioned that the pipe to be acted upon is brought midway between the die stock handles.

Having thus described by invention, what I claim is:

1. In a die stock, the combination of a hollow frame, a plurality of dies carried by the frame on one side thereof, a pipe guide member movably carried by the frame on the opposite side of the hollow, means for holding it in alinement with either of said dies, and means for varying the size of the pipe guide opening.

2. In a die stock, the combination of a frame, a plurality of sets of dies carried by

the frame, a pipe guide member shiftably carried by the frame, means for clamping said member in a position in alinement with either of said sets of dies, and means for varying the size of the pipe guide opening without changing said alinement.

3. In a die stock, the combination of a frame, a plurality of sets of dies for different sizes of pipe carried by the frame, a guide member having an adjustable throat to embrace different sizes of pipe and movably carried by the frame, and means for rigidly securing it in position to embrace a pipe acted upon by any of said sets of dies.

4. In a die stock, the combination of a frame, a plurality of sets of dies carried thereby, a pipe guide having a single bore of variable size, and means for slidably carrying the guide on the frame.

5. In a die stock, the combination of a hollow frame, alined handles at opposite ends thereof, a plurality of dies each arranged midway between the handles and an adjustable bushing movably carried by the frame and adapted to be brought into alinement with any one of said dies.

6. In a die stock, the combination of a frame, a plurality of dies carried thereby, an adjustable pipe guide bushing, a guide on the frame along which the bushing is slidable and means for clamping the bushing in a different position along the guide opposite either of said dies.

7. In a die stock, the combination of a frame, a plurality of dies carried thereby, an adjustable pipe guide bushing, a guide on the frame for positioning the bushing, means for clamping the bushing in different positions along the guide opposite either of said dies, and manually operable members for actuating the clamping means.

8. In a die stock, the combination of a hollow frame, handles removably secured to the frame, a plurality of sets of pipe dies arranged side by side around one side of the frame, an arcuate guide extending around the opposite side of the frame, and surrounding an opening through which the pipe to be acted upon may project, and an adjustable bushing for embracing the pipe movable along said guide.

9. A die stock comprising a hollow frame, axially alined handles secured to each end of the frame, a plurality of sets of standard dies secured side by side around one side of the frame, an arcuate guideway along one side of the frame, an adjustable pipe guide bushing slideable along said guideway and adapted to be brought into alinement with either of said sets of dies, and means for clamping the bushing in operative position for any of the sets of dies.

10. A die stock comprising a hollow frame, axially alined handles removably secured to each end of the frame, a plurality

- of sets of standard dies secured side by side around one side of the frame, an opening in the opposite side of the frame, guideways along each side of the opening, an adjustable 5 pipe guide bushing slidable on said guideways and adapted to be brought into alignment with either of said sets of dies, said guideways having notches, a movable member carried by the bushing engaging said notches for locking it in position, and a depressible plunger carried by the bushing for 10 releasing said locking element.
11. In a die stock, the combination of a frame, a plurality of sets of pipe dies arranged side by side on one side of the frame, a guide on the frame on its opposite side, and a sleeve member slidably mounted on 15 said guide and adapted to be positioned in registration with any of the sets of dies.
- 20 12. In a die stock, the combination of a hollow polygonal frame, a plurality of sets of pipe dies arranged about the frame, an arcuate guide carried by the frame, and a
- pipe guide slidably mounted on the arcuate guide and adapted to be positioned in registration with any of the sets of dies. 25
13. In a die stock, the combination of a hollow polygonal frame, a plurality of sets of pipe dies arranged about one side of the frame, an arcuate guide carried by the frame 30 on its opposite side, a slidable member mounted in said guide and having an opening, and means for guiding various sizes of pipe extending through said opening.
14. In a die stock, the combination of a hollow polygonal frame, a plurality of sets of pipe dies arranged side by side about one side of the frame, an arcuate guide carried by the frame on its opposite side, a slidable member mounted in said guide, and a pipe 35 guide having an adjustable throat carried by said member. 40

In testimony whereof, I hereunto affix my signature.

JOHN B. MARTENS.
